HYGROMETER

Filed Aug. 16, 1933

UNITED STATES PATENT OFFICE

2,092,264

HYGROMETER

Hugh G. Ross, Ottawa, Ontario, Canada

Application August 16, 1933, Serial No. 685,483

2 Claims. (Cl. 73—338)

My invention relates to the design of a hygrometer for measuring the moisture content of the air. The purpose of my invention is to provide an inexpensive instrument which gives a direct 5 numerical reading of percent relative humidity without calculation, use of charts, or interpolation of curves, and still employs the accurate wet and dry bulb type of measurement. This is accomplished by adding to the regular type of wet 10 and dry bulb hygrometer, a simple mechanical arrangement which makes it direct reading.

The objects and advantages of the invention will be apparent from the following specification.

In the drawing illustrating preferred forms 15 of my invention:

Figure 1 shows my preferred form wherein two sliding members are used for setting opposite the thermometer levels;

Figure 2 shows a partly cut-away side view of 20 the instrument as shown in Figure 1.

Referring more particularly to the drawing, 1 is the frame or body of the instrument, 2 and 3 are similar thermometer tubes, 15 is a water container held by clip 16 and feeding water through 25 wick 17 to keep bulb of thermometer 2 wet. 4 and 5 are the scales of the thermometers being similar and graduated in degrees Fahrenheit. The part thus far described is common to all 30 wet and dry bulb hygrometers.

30 In the preferred form of my invention I employ two slots 6 and 7 in which are mounted two sliding members 8 and 9. These members can be slid the full extent of their respective slots and the small pointer on the side of each member is 35 to be placed opposite the level of the liquid in each thermometer tube. The moving plate 10 is mounted on both sliding members being free to rotate about the pin 12 on member 8 and having in it a slot 11 which slides on and turns about pin 40 13 of member 9. The extent of the body 1 is such that the plate is free to slide up and down as the sliding members 8 and 9 move up and down, and it can also rotate about pin 12 as member 9 moves with respect to member 8. The 45 amount which plate 10 may rotate about pin 12 is limited to that required by the extreme differential which would occur normally between the two thermometer readings.

On the plate 10 are a number of figures representing 50 different values of percent relative humidity. These are arranged in such position that the

correct one appears in the aperture 14 for any given setting of the two sliding members 8 and 9. To insure the figure being centered in aperture 14, the edges of slots 6 and 7 may be notched, or a rectangular frame may be placed around each figure as shown at 25.

It is obvious that I might derive the same result by having the plate 10 pivot about pin 13 and have a slot to slide on pin 12, or that the plate 10 project downwardly instead of upwardly in 10 which case the aperture 14 would be near the bottom of the instrument.

From the foregoing description taken in connection with the accompanying drawing, it will be manifest that a hygrometer of the wet and 15 dry bulb type is provided which will give direct numerical reading of percent relative humidity but, as many changes could be made in the above description and many apparently widely different embodiments of the invention may be constructed 20 within the scope of the appended claims without departing from the spirit or scope thereof, it is intended that all matters contained in the said accompanying specification and drawing shall be interpreted as illustrative and not in a limitative 25 or restrictive sense.

Having thus described the invention, what I claim as new and desire to secure by Letters Patent is:—

1. In a hygrometer, a frame, two thermometer 30 tubes, means for keeping the bulb of one tube wet, an aperture in said frame, slots in said frame parallel to each tube, a member slidably mounted in each slot, a plate adjustably attached to both 35 slidable members so that it is capable of movement parallel to the slots or of orientation about either member as centre, numeric values of percent relative humidity printed on the plate in such position that the proper one shows through said aperture when the slidably mounted members 40 are set opposite the thermometer levels.

2. In a hygrometer, a frame, two thermometer tubes, means for keeping the bulb of one tube wet; slots in said frame paralleling said tubes, an 45 aperture in said frame, a movable indicia bearing plate behind said frame, and indicators rotatably connected with said plate and sliding in said slots which when set opposite thermometer levels gives direct reading of said indicia indicating percent relative humidity through said aperture. 50

HUGH G. ROSS.
